(57) **CLAIM**

The ornamental design for a wall plate, as shown and described.

DESCRIPTION

FIG. 1 is a front perspective view of a first embodiment of a wall plate showing my new design;

FIG. 2 is a front elevational view;

FIG. 3 is a rear elevational view;

FIG. 4 is a right side elevational view;

FIG. 5 is a left side elevational view;

FIG. 6 is a top plan view;

FIG. 7 is a bottom plan view;

FIG. 8 is a front perspective view of a second embodiment of a wall plate showing my new design;

FIG. 9 is a front elevational view;

FIG. 10 is a rear elevational view;

FIG. 11 is a right side elevational view;

FIG. 12 is a left side elevational view;

FIG. 13 is a top plan view;

FIG. 14 is a bottom plan view;

FIG. 15 is front perspective view of a third embodiment of a wall plate showing my new design;

FIG. 16 is a front elevational view;

FIG. 17 is a rear elevational view;

FIG. 18 is a right side elevational view;

FIG. 19 is a left side elevational view;

FIG. 20 is a top plan view;

FIG. 21 is a bottom plan view;

FIG. 22 is front perspective view of a fourth embodiment of a wall plate showing my new design;

FIG. 23 is a front elevational view;

FIG. 24 is a rear elevational view;

FIG. 25 is a right side elevational view;

FIG. 26 is a left side elevational view;

FIG. 27 is a top plan view; and,

FIG. 28 is a bottom plan view.

The broken-line disclosure in the views represents portions of the article in which the claimed design is embodied, but which form no part of the claimed design.
